13 Claims.

(Cl. 62—5)

This invention relates to the art of refrigeration and more particularly to an absorption refrigerating system involving unique control and regulating features.

This invention particularly relates to three-fluid absorption refrigerating systems of the type in which a circulating motor is hermetically sealed within the system in order to circulate the fluids therein. Motors of this type must be lubricated. However, considerable difficulty may arise in handling and installing the system due to the fact that under some circumstances the lubricant in the motor shell may be displaced by foreign material, such as absorption solution, and once displaced it will be very difficult to return the lubricant to its normal environment without materially reconstructing the apparatus. Moreover, it may occur that the system will not be maintained in upright condition during handling and installation with the result that the lubricant will be spilled out of the motor casing and will not later be returned thereto.

In order to obviate these difficulties it is an object of the present invention to provide an absorption refrigerating system of the above described character in which the motor is lubricated by a material which is not fluid at normal atmospheric temperatures and which will flow at the temperatures maintained by the heat generated by the motor winding in order to perform its lubricating function efficiently.

It is a further object of the present invention to provide an absorption refrigerating system of the above referred to type in which the lubricant in its non-fluid state imposes sufficient drag upon the rotating portions of the motor to block the same until the lubricant has been liquefied or substantially so, for example by the application of heat thereto.

It is a further object of the present invention to provide an absorption refrigerating system in which operation of the circulating motor is prevented after energization thereof by reason of the lubricant blocking the motor for a period of time sufficient to permit the boiler to come into full operation; that is, to discharge refrigerant vapor to the condenser in order that the same may be liquefied and re-evaporated in the evaporator to produce a useful refrigerating effect.

With some lubricants, such as those having a high paraffin content, the period required to liquefy the same by the heat generated by the small current flowing through the winding of the

motor is excessive wherefore it is an object of the present invention to provide a special heating element which functions to come into operation substantially simultaneously with the boiler-heater and which will render the motor lubricant fluid at substantially the same time that the boiler discharges refrigerant vapor after which the motor will be energized and the heating element de-energized to place the system in normal operating condition.

It is a further object of the present invention to provide an absorption refrigerating system including a circulator, the rotor of which is immersed in a non-fluid lubricant in which the lubricant is rendered fluid by waste heat from the boiler-heater at substantially the time that the boiler comes into full operation; that is, discharges refrigerant vapor, and in which the motor is energized after the lubricant is rendered fluid and in response thereto in order to place the system in normal operation.

It is still another object of the present invention to provide an absorption refrigerating system which includes a lubricated circulator provided with a lubricant heater for softening the lubricant, which heater is de-energized after softening of the lubricant in response to temperature change in a particular portion of the refrigerating system when such a change is produced as an incident to normal starting operation of the refrigerating system.

Other objects and advantages of the invention will become apparent as the description proceeds when taken in connection with the accompanying drawings, in which:

Figure 1 is a diagrammatic representation of a three-fluid absorption refrigerating system embodying the present invention;

Figure 2 is a partial sectional elevational view drawn to an enlarged scale of the motor circulator unit illustrated in Figure 1;

Figure 3 is a partial schematic illustration of a modified form of the invention.

Referring now to the drawings in detail and first to Figure 1 thereof, there is illustrated a three-fluid absorption refrigerating system comprising a boiler B, an analyzer D, an air-cooled rectifier R, a tubular air-cooled condenser C, an evaporator E, a gas heat exchanger G, a tubular inclined air-cooled absorber A, a liquid heat exchanger L, a solution reservoir S, and a circulating fan F which is driven by an electrical motor M. These elements are suitably connected by various conduits to form a plurality of gas and liquid circuits constituting a complete refrigerat-

ing system to which reference will be made in more detail hereinafter.

The above described refrigerating system will be charged with a suitable absorbent, such as water, a suitable refrigerant, such as ammonia, and an inert pressure equalizing medium preferably a dense inert gas like nitrogen.

The boiler B is arranged to be heated by a gas burner H which will be described in more detail hereinafter. The application of heat to the boiler B generates refrigerant vapor from the solution therein contained. The vapors so generated pass upwardly through the analyzer D in counterflow to the strong solution flowing downwardly therethrough. After traversing the analyzer D the vapor is conveyed from the upper portion thereof to the upper portion of the condenser C by means of a conduit 11 which includes the rectifier R.

The lean solution formed in the boiler by the generation of refrigerant vapor therefrom is conveyed from the boiler to the solution reservoir S by way of the conduit 12, the liquid heat exchanger L and a finned looped conduit 13 which also serves as a solution precooler.

The solution reservoir S is vented by means of a conduit 14 which connects to the suction conduit 15 of the circulating fan F. The conduit 15 extends between the suction side of the fan F and the upper portion of the absorber A.

The lean solution is conveyed from the reservoir S to the conduit 15 adjacent its point of connection with the absorber A by means of a gas lift pumping conduit 16. Pumping gas is supplied to the conduit 16 by means of a conduit 17 which is connected between the discharge conduit 18 of the circulating fan F and the gas lift pump 16 below the liquid level normally prevailing therein and in the solution reservoir S.

The lean solution flows downwardly through the absorber A in counterflow relationship to a rich mixture of inert gas and refrigerant vapor which is supplied to the bottom portion of the absorber from the evaporator in a manner to be described hereinafter.

In its traverse through the absorber the lean solution absorbs refrigerant vapor from the gas mixture flowing therethrough and the resulting heat of absorption is rejected by the cooling fins to cooling air flowing over the exterior walls of the absorber vessel.

The strong solution thus formed in the absorber is conveyed therefrom to the upper portion of the analyzer D by way of the conduit 19, the liquid heat exchanger L, and a conduit 20 thus completing the absorption solution circuit.

Lean inert gas is formed in the absorber A by the absorption of refrigerant vapor and is then conveyed from the upper portion of the absorber to the suction side of the circulating fan F by means of the conduit 15. The inert gas is placed under pressure in the fan F and is then conveyed therefrom to the lower portion of the evaporator E by way of the conduit 18, the outer path of the gas heat exchanger G and an evaporator gas supply conduit 22.

The refrigerant vapor which is supplied to the condenser C is liquefied therein by heat exchange relationship with atmospheric air and is then conveyed therefrom to the bottom portion of the evaporator E by way of the conduit 23 and a conduit 24 which includes a downwardly extending U-shaped looped portion which is designed to carry a liquid seal and a pressure balancing column of the liquid refrigerant. The conduits 23

and 24 are vented by means of a conduit 25 to the rich gas side of the gas heat exchanger G. As a result of this construction the pressure prevailing in the condenser and the condenser side of the conduit 24 is that prevailing on the discharge side of the evaporator whereas the pressure prevailing on the discharge side of the conduit 24 is that prevailing at the inlet to the evaporator. This pressure difference is compensated by a pressure balancing liquid column which is supported in the condenser side of the conduit 24.

The evaporator E may be of any desired type of construction. However, as diagrammatically illustrated herein, it is of the type in which the high velocity gas stream flowing through the evaporator serves to sweep or drag liquid refrigerant upwardly therethrough as it is evaporating to produce refrigeration. A preferred construction of this type evaporator is disclosed and claimed in the co-pending application of Curtis C. Coons and William H. Kitto, Serial No. 220,189, filed July 20, 1938. An anti-blocking and overflow drain 27 is connected between the upper portion of the bottom conduit in the evaporator E and the strong solution return conduit 19.

The liquid refrigerant supplied to the bottom portion of the evaporator E meets a high velocity gas stream flowing upwardly therethrough with the result that the liquid refrigerant is propelled upwardly through the evaporator as it is evaporating into the gas stream to produce useful refrigeration.

The top portion of the evaporator is provided with a large diameter finned box-cooling conduit 28 into which both the liquid and gas discharge. The gas flows at a slow rate through this conduit, hence the same is inclined rearwardly in order to permit liquid to flow by gravity. The resulting rich gas and unevaporated material in the evaporator is conveyed from the conduit 28 into the rich gas side of the gas heat exchanger G by means of a conduit 29. After traversing the rich gas side of the gas heat exchanger the rich gas and unevaporated material is drained therefrom into the bottom portion of the absorber A by means of the conduit 30. Thus, the conduit 30 serves as a rich gas return conduit and as an evaporator drain. The rich gas then flows upwardly through the absorber A in counterflow relationship with the lean solution flowing downwardly therethrough in the manner heretofore described.

It will be noted that with the construction thus provided evaporator drainage is conveyed to the conduit 19 in a manner such that it cannot reach the circulating fan and the fan is so connected to the absorber that lean solution cannot be conveyed thereto from the lean solution supply lines. This is of considerable importance in preventing absorbing solution from finding its way to the motor shell, as will be explained in more detail hereinafter.

Referring now to Figures 1 and 2, it is apparent that the fan casing F carries a sealed motor shell 35 depending therefrom. The motor M consists of a rotating element 36 which is mounted within the shell and a stationary field winding or stator structure 37 which is mounted on the outside of the shell whereby the magnetic circuit for the induction rotor 36 must pass through the shell 35. The rotor is supported on suitable bearing assemblies indicated generally at 38 and 39 within the shell 35. The motor shaft 40 passes

through the bearing 38 and carries a suitable fan within the fan housing 41 in a conventional manner.

The depending motor shell 35 is filled with a suitable lubricant up to the level of the line indicated generally at 44; that is, the rotor is completely submerged and part of the bearing 38 is submerged in the lubricant.

One such lubricant is paraffin and it is obtainable in a long range of melting points and specific gravity. By selecting paraffin of the proper melting point or by mixing it with other lubricants, almost any melting point desired can be obtained. This lubricant has the characteristic that it is non-fluid at ordinary room temperatures but will become fluid when heated above that temperature in order to lubricate the bearings to permit the motor to rotate. In its non-fluid state the drag of this lubricant is sufficient to stall the rotor or the motor.

In this connection it should be emphasized that this motor is very small and develops only sufficient power to circulate the inert gas with a few inches of water pressure differential, hence the lubricant drag is easily sufficient to stall the same.

In order to apply heat to the lubricant which is contained within the shell 35 to render the same fluid, a suitable electrical heating element 45 embraces the lower end of the motor shell 35 below the stator 37 of the electrical motor M. The heater 45 is encased in a suitable refractory channel shaped element 46 which protects the stator and its associated windings from the heat of the element 45 and also prevents loss of heat therefrom.

A housing 47 of insulating material is suitably attached to the bottom portion of the motor shell 35 beneath the heater 45 and is provided with a switching enclosure or chamber 48. An electrical switch 49 is enclosed within the chamber 48. A bracket 50 is attached to the bottom portion of the shell 35 and carries a thermostatic strip or disc 51, as may be desired, directly above the switch 49. The disc 51 is provided with an actuating button 52 which may be made of a composition insulating material and is positioned to strike the movable element 53 of the switch 49 to actuate the same.

As was mentioned previously a heater H is provided for the boiler B. Gas is supplied to the heater H from a suitable source of supply through a conduit 55 which includes a solenoid valve V. A small by-pass 56 is provided around the valve V in order to maintain a small ignition flame on the heater H. Also included in the conduit 55 adjacent the burner is a suitable thermostatic safety cut-off device 57 which is arranged to discontinue supply of fuel to the burner completely upon failure of flame thereupon, as for example in case the small igniting or pilot flame is extinguished by a draft or the like.

The apparatus is controlled by means of a suitable thermostatic switching mechanism indicated generally at 60 and provided with a capillary conduit 61 which connects to a fluid containing bulb 62 positioned to be influenced by temperature changes at or adjacent the evaporator E. The exact construction of the thermostatic switching mechanism 60 is conventional and need not be disclosed in detail herein. Power is supplied to the apparatus from a pair of electrical conductors 63 and 64. The conductor 63 connects directly to the solenoid valve V which is then connected by means of a conductor 65 to 75

the switching mechanism 60. The switching mechanism 60 is connected to the winding 66 of the motor stator 37 by means of a conductor 67 and a branch conductor 68. The switching mechanism 60 is also connected to the heating element 45 by the conductor 67 and a second branch conductor 69.

The heating element 45 is then connected to the upper contact 70 of the switch 49 by means 10 of a conductor 71. The winding 66 of the stator 37 is connected to the lower contact 72 of the switch 49 by means of the conductor 73.

As may readily be seen from a perusal of Figure 2, the movable element 53 of the switch 49 is arranged to contact either the upper connector 70 or the lower connector 72 thereof. The movable element 53 of the switch 49 is connected directly to the supply conductor 64, thus completing the electrical control circuit.

The operation of this form of the invention except insofar as the same has already been disclosed in connection with the construction of the refrigerating apparatus per se is as follows: Assuming a demand for refrigeration the thermostatic switch 60 will complete the electrical circuit between the conductors 65 and 67. This will then energize the solenoid valve V to permit full flame operation of the burner H. Likewise current will flow from the switching mechanism 60 by the following circuits 67, 69, 45, 71, 70, 53 and 64, thereby energizing the heater 45. Due to the fact that the thermostat 51 will be flexed upwardly, as shown in Figure 2, to permit contact between the elements 53 and 70 of the switch 49, the heater will be in condition to be energized but the winding 66 of the motor will be open circuited at 72. Consequently heat will be applied to the boiler B to heat the contents thereof to the boiling point after which refrigerant vapor 30 will be produced and heat will be applied by the element 45 to the shell 35 and the contents thereof in order to render the lubricant fluid so that the same will not block rotation of the rotor 36 upon energization of the winding 66. The motor, 35 heater, lubricant, boiler and boiler-heater are all inter-related in any given installation. Consequently with a given lubricant, boiler and boiler-heater the heater 45 will be constructed to render the lubricant fluid substantially simultaneously with the expulsion of refrigerant vapor from the contents of the boiler. When the shell 35 has been heated sufficiently to render the lubricant therein contained fluid, the temperature of the shell will be at a value sufficiently to 40 actuate the thermostat 51 which will then flex downwardly, as viewed in Figure 2, separating the contacts 53 and 70 and closing the contacts 53 and 72, thereby de-energizing the heater 45 and energizing the motor stator winding 66. The apparatus is now in normal operating condition and will continue in that condition until the temperature at or adjacent the evaporator has been lowered to the predetermined point for which the thermostatic switching mechanism 60 is set. During operation of the apparatus the heat generated by the motor stator winding is 45 ample sufficient to maintain the lubricant in the fluid condition and to prevent the same from imposing a stalling or blocking drag upon the rotor 36.

When the temperature of the refrigerated space reaches that for which the control mechanism is set, the thermostatic mechanism 60 de-energizes the entire system whereupon the valve V closes, the burner H returns to low flame or

pilot flame operation and the motor is de-energized.

If the motor remains de-energized for an appreciable period of time, and it usually will remain de-energized for such a period of time, the motor will cool sufficiently to cause congealation of the lubricant within the shell 35 and the thermostat 51 will consequently flex upwardly to the position shown in Figure 2 to open the circuit between the connectors 72 and 53 and to close 10 the circuit between the connectors 70 and 53, thereby re-conditioning the electrical circuit for normal starting operation.

As at present advised the illustrated construction is the preferred arrangement; however, the 15 thermostatic cut-out for the lubricant heater may be arranged to de-energize the heater in response to a change in the condition of another portion of the system induced by energization of the system. For example, the thermostatic cut-out for the lubricant heater could be arranged to respond to the temperature of some portion of the pipe 11. This pipe is heated by hot vapor enroute to the condenser. There is a time lag between initiation of full flame operation of the burner and heating of this pipe which will allow sufficient heating of the lubricant to render the same fluid and will produce the desired lag in operation of the motor with respect to the burner.

In Figure 3 there is illustrated a modified form of the invention. This form of invention is designed and intended to be utilized with a refrigerating system identical with that disclosed in Figure 1 except insofar as changes have been made 35 and illustrated in Figure 3. Therefore, only those portions of the apparatus which have been altered are illustrated in Figure 3 in order to avoid unnecessary duplication of illustration. Certain portions of the apparatus illustrated in Figure 3 being identical with apparatus previously illustrated and described in Figures 1 and 2, they are given the same reference characters primed.

In the form of the invention illustrated in Figure 3 the products of combustion from the heater H' are discharged through a central flue 80 of the boiler B'. After traversing the flue 80 the products of combustion are conveyed to a suitable point of disposal by means of an insulated flue system 81.

The flue 81 joins a valve chamber 82 which is located adjacent the motor M'. The valve chamber 82 is branched, one branch 83 extending upwardly into communication with a shell 84 which surrounds the lower portion of the motor shell 35' and in turn communicates with an off-take flue 85 which ultimately discharges into a flue 86 which conveys products of combustion to a point of ultimate disposition. The valve chamber 82 also communicates with a branch conduit 87 which communicates with the lower end of the flue 86.

A flap valve 88 is pivotally mounted within the valve chamber 82 and is arranged to be actuated by means of a crank 89 which connects to an actuating rod 90.

The end of the rod 90 remote from the crank 89 carries an electrical switch contact 91 which is adapted to make contact with a stationary contact 92.

In this form of the invention electrical energy is supplied to the apparatus through the line conductors 93 and 94. The conductor 94 is connected to a thermostatic switch mechanism 95

by means of the conductor 96. It will be understood that the thermostatic switch mechanism 95 will be positioned to respond to the temperature of the evaporator or of the space being refrigerated as may be desired. The other side of the thermostatic switch 95 is connected by means of a conductor 97 to a solenoid 98 which is then connected by means of a conductor 99 to the other line conductor 93.

The conductor 94 also connects to a conductor 100, one end of which is connected to the valve V' and the other end of which is connected to one contact of a solenoid operated switch 101. The valve V' is also connected by means of a conductor 102 to a second solenoid operated switch 103. The switches 101 and 103 are arranged to be opened or closed simultaneously by means of a solenoid armature 104 which is arranged to be actuated by the solenoid coil 98.

The other contact of the solenoid switch 103 is connected to the conductor 99 by means of a conductor 105. The other contact of the solenoid switch 101 is connected to the contact 92 by means of a conductor 106. The movable contact 91 is connected to the field winding 66' of the stator 37' of the motor M' by means of a conductor 107. The winding 66' is also connected directly to the line conductor 93. This completes the electrical control circuit.

The actuating arm 88 of the valve 88 and switch contact 91 is arranged to be operated by means of a thermostatic bellows 110 which is arranged to be responsive to the temperature of the motor shell 35' by means of a bulb and capillary tube connection 111 and is connected to operate the arm 88 by means of a snap-acting toggle mechanism 112.

It is readily apparent that the switch contacts 91 and 92 are in open circuit position; that is, in a position to de-energize the motor when the thermostatic bellows 110 has contracted in which position it has actuated the rod 90 to shift the valve 88 in position to close communication between the conduits 87 and the valve chest 82.

The operation of this form of the invention is as follows: Assuming a demand for refrigeration the thermostatic switch mechanism 95 will close the circuit between the conductors 93 and 94, thus energizing the solenoid coil 98. Upon energization of the solenoid coil 98, the solenoid 104 will be lifted and the solenoid switches 101 and 103 will be moved to closed circuit position. The valve V' will now be energized by the following circuit: 94, 100, 102, 103, 105, 99 and 93. This circuit will of course cause full flame operation to be initiated at the burner H' in the usual manner. However, the motor M' is not yet energized due to the open circuit condition existing at the electrical contacts 91 and 92 and the valve 88 will be in the position illustrated in Figure 3 wherefore waste products of combustion from the burner H' will traverse the conduit 81, valve chest 82 and conduit 83 in order to pass through the motor shroud 84 to heat the motor shell 35' and the oil therein contained. This condition of operation will continue until such time as sufficient heat has been applied to the shell 35' in order to render the lubricant therein contained fluid and thus to remove the blocking influence from the motor. Once this condition is reached the temperature of the shell 35' reaches a value sufficient to cause expansion of the thermostatic device 110 which then, through the snap-acting mechanism 112, quickly closes the electric contacts 91 and 92 and shifts the valve 88 to the

dotted line position of Figure 3, thereby preventing further discharge of products of combustion around the shell 35' and directing all the products of combustion directly to waste through the conduits 87 and 88.

The closure of the electrical circuits between the contacts 91 and 92 now energizes the electrical motor M' through the following circuits: 94, 100, 101, 106, 92, 91, 107, 66' and 93.

The system is now in normal operation and continues in that condition until such time as the evaporator or the space being refrigerated shall have reached a temperature for which the thermostatic switch 95 is set, whereupon the same will open allowing the solenoid to drop and open circuit the solenoid switches 101 and 103, thus de-energizing both the burner H' and the circulating motor M'. During operation of the system sufficient heat is applied to the shell 35' by the winding 66' of the motor M' to maintain the lubricant therein in a fluid condition in order that the same may perform its lubricating function without imposing a stalling load upon the very small motor which is utilized.

After de-energization of the system the shell 35' and its contents will gradually cool which will allow the lubricant to become non-fluid and eventually will reach a temperature such that the thermostat 110 will contract to the position shown and will correspondingly actuate the valve 88 to the position illustrated and will open circuit the contacts 91 and 92, thus restoring the system to its initial position and rendering the same in condition for re-energization with response to a demand for refrigeration.

Though the bulb 111 in this form of the invention has been illustrated as being applied directly to the motor shell 35' as that is now believed to be the preferred construction, it is obvious that the same could be applied to other portions of the system, for example, one of the flues 81, 85, 86 and the like.

The present invention provides a very advantageous arrangement in that loss of lubricant from the motor shell and/or displacement thereof by liquid refrigerant or absorption solution during transit of the refrigerating system and installation thereof is absolutely prevented by reason of the fact that the lubricant is in a non-fluid state prior to operation thereof. This is of considerable importance as it is impossible to insure that the apparatus will be maintained in upright position during handling and shipment.

The lubricant also has an advantageous effect with respect to the operation of the refrigerating system and control thereof in that the arrangement herein provided automatically prevents circulation of absorption solution and inert gas until the boiler has been fully heated and liquid refrigerant has been supplied to the evaporator at which time the system is conditioned to go into complete operation. Considerable loss is entailed if the inert gas is circulated during the period of time required to bring the liquid in the boiler up to the boiling temperature because this circulates absorption solution thereby continuously removing the heated liquid from the boiler and cooling the same in the absorber and it also circulates inert gas warmed by contact with the solution in the absorber through the evaporator thus adding to the net refrigerating load when liquid refrigerant is eventually supplied to the evaporator. The present arrangement obviates these difficulties.

Thus, the present invention provides a very

advantageous construction of an absorption refrigerating system together with the control mechanism therefor which insures that lubricant will not be lost from the motor shell during transit, handling and installation and which provides a construction whereby the lubricant is rendered fluid prior to energization of the motor and also in which the time period required to condition the motor for energization is so correlated through the control for the boiler-heater that the boiler is brought up to operating condition just prior to energization of the motor whereby the system goes into complete operation immediately the motor is energized and no loss of heat is entailed in the preliminary heating of the boiler analyzer assembly.

This type of control is not only economical but is also more efficient than the previously known simultaneous energization type of controls which have been used on this type of refrigerating system.

While the invention has been illustrated and described herein in considerable detail, various changes may be made in the arrangement, construction and proportion of parts without departing from the spirit of the invention or the scope of the appended claims.

I claim:

1. Absorption refrigerating apparatus including a boiler, an absorber, a liquefier and an evaporator connected in circuit, means for heating said boiler, a motor driven fluid circulator including a motor rotor sealed in said apparatus and at least partially immersed in a lubricant which has a viscosity sufficiently high at atmospheric temperatures to prevent operation of said rotor, means for heating said lubricant sufficiently to lower the viscosity thereof to a value such that operation of said rotor is not prevented thereby, refrigeration demand responsive means for energizing said boiler and lubricant heating means, and means for energizing said motor and for rendering said lubricant heating means inoperative in response to a change in the thermal condition of a portion of the apparatus induced as a consequence of energization of said heaters.

2. Absorption refrigerating apparatus including a boiler, an absorber, a liquefier and an evaporator connected in circuit, means for heating said boiler, a motor driven fluid circulator including a motor rotor sealed in said apparatus and at least partially immersed in a lubricant which has a viscosity sufficiently high at atmospheric temperatures to prevent operation of said rotor, an electrical heater for said lubricant sufficiently to lower the viscosity thereof to a value such that operation of said rotor is not prevented thereby, refrigeration demand responsive means for energizing said boiler heating means and lubricant heater, and means for energizing said motor and for rendering said lubricant heater inoperative in response to a change in the thermal condition of a portion of the apparatus induced as a consequence of energization of said heater.

3. Absorption refrigerating apparatus including a boiler, an absorber, a liquefier and an evaporator connected in circuit, a combustible fuel burner for heating said boiler, a motor driven fluid circulator including a motor rotor sealed in said apparatus and supported in a lubricant which has a viscosity sufficiently high at atmospheric temperatures to prevent operation of said rotor, and means for conducting waste products of combustion from said boiler into heat exchange relationship with said lubricant to heat

said lubricant sufficiently to lower the viscosity thereof to a value such that operation of said rotor is not prevented thereby.

4. Absorption refrigerating apparatus including a boiler, an absorber, a liquefier and an evaporator connected in circuit, a combustible fuel burner for heating said boiler, a motor driven fluid circulator including a motor rotor sealed in said apparatus and contacted by a lubricant which has a viscosity sufficiently high at atmospheric temperatures to prevent operation of said rotor, means for conducting waste products of combustion from said boiler into heat exchange relationship with said lubricant to heat said lubricant sufficiently to lower the viscosity thereof to a value such that operation of said rotor is not prevented thereby, and means for diverting said products out of heat exchange relation with said lubricant when the same has been rendered fluid.

5. Absorption refrigerating system comprising an inert gas circuit including an evaporator and an absorber, a solution circuit including a boiler and said absorber, means for liquefying refrigerant vapor produced in said boiler and for supplying the liquid to said evaporator, means for heating said boiler, a motor driven fluid circulator including a motor rotor sealed within said system and immersed in a lubricant which is substantially solid at atmospheric temperatures, means for heating said lubricant for rendering the same fluid, refrigeration control means for controlling the operation of said boiler and lubricant heating means, and means responsive to the temperature of said lubricant for de-energizing said lubricant heating means and for energizing said motor when said lubricant is rendered fluid.

6. Absorption refrigerating system comprising an inert gas circuit including an evaporator and an absorber, a solution circuit including a boiler and said absorber, means for liquefying refrigerant vapor produced in said boiler and for supplying the liquid to said evaporator, means for heating said boiler, a motor driven fluid circulator including a motor rotor sealed within said system and mounted in a lubricant which is substantially solid at atmospheric temperatures, means for heating said lubricant for rendering the same fluid, refrigeration control means for controlling the operation of said boiler and lubricant heating means, means responsive to the temperature of said lubricant for de-energizing said lubricant heating means and for energizing said motor when said lubricant is rendered fluid, said lubricant being maintained in fluid condition by the heat generated by said motor.

7. Absorption refrigerating system comprising an inert gas circuit including an evaporator and an absorber, a solution circuit including a boiler and said absorber, means for liquefying refrigerant vapor produced in said boiler and for supplying the liquid to said evaporator, a combustible fuel burner for heating said boiler, a motor driven fluid circulator including a motor rotor sealed in said system and contacted by a lubricant which is non-fluid at atmospheric temperatures, means for disposing of waste products of combustion from said boiler including a branch in heat transfer relationship with said motor and a branch not in heat transfer relationship with said motor, control mechanism for regulating the operation of said fuel burner, and control mechanism for directing waste products of combustion through said branch in heat transfer relation with said motor until said lubricant is

rendered fluid and for then directing such products through the said branch not in heat transfer relationship with said motor.

8. Absorption refrigerating system comprising an inert gas circuit including an evaporator and an absorber, a solution circuit including a boiler and said absorber, means for liquefying refrigerant vapor produced in said boiler and for supplying the liquid to said evaporator, a combustible fuel burner for heating said boiler, a motor driven fluid circulator including a motor rotor sealed in said system and submerged in a non-fluid lubricant which is non-fluid at atmospheric temperatures, means for disposing of waste products of combustion from said boiler including a branch in heat transfer relationship with said motor and a branch not in heat transfer relationship with said motor, control mechanism for regulating the operation of said fuel burner, control mechanism for directing waste products of combustion through said branch in heat transfer relation with said motor until said lubricant is rendered fluid and for then directing such products through the said branch not in heat transfer relationship with said motor, said lubricant being maintained in fluid condition by the heat generated by said motor.

9. Absorption refrigerating apparatus including a boiler, an absorber, a liquefier, a motor driven fluid circulator and an evaporator connected in circuit, means for heating said boiler, said motor driven fluid circulator including a motor rotor sealed in said apparatus and immersed in a lubricant which has a viscosity at atmospheric temperatures such that operation of said rotor is prevented, means for conveying waste products of combustion from said boiler heating means into heat exchange relationship with said lubricant to heat said lubricant sufficiently to lower the viscosity thereof to a value such that operation of said rotor is not prevented thereby, refrigeration demand responsive means for energizing said boiler heater, and means for energizing said motor and for diverting waste products of combustion through a disposal path not in heat exchange relationship with said lubricant in response to a change in the thermal condition of a portion of the apparatus induced as a consequence of energization of said heaters.

10. Absorption refrigerating apparatus comprising a boiler, a liquefier, an evaporator and a condenser connected in circuit, a fluid circulator sealed in said apparatus, a driving device for said fluid circulator sealed in said apparatus, a lubricant for said driving device, means for heating said generator, means for heating said lubricant, control means for rendering said heating means operative in response to a demand for refrigeration, and means responsive to a change in the condition of a part of said apparatus induced as a consequence of operation of said heating means for rendering said lubricant heating means inoperative and for rendering said driving device operative.

11. Absorption refrigerating apparatus comprising a boiler, a liquefier, an evaporator and a condenser connected in circuit, a fluid circulator sealed in said apparatus, a driving device for said fluid circulator sealed in said apparatus, a lubricant for said driving device, means for heating said generator, means for heating said lubricant with waste heat from said generator heating means, control means for rendering said heating means operative in response to a demand for refrigeration, and means responsive to a change

in the condition of a part of said apparatus induced as a consequence of operation of said heating means for rendering said lubricant heating means inoperative and for rendering said driving device operative.

12. Absorption refrigerating apparatus comprising a boiler, a liquefier, an evaporator and a condenser connected in circuit, a fluid circulator sealed in said apparatus, a driving device for said fluid circulator sealed in said apparatus, a lubricant for said driving device, a combustible fuel burner for said generator, means arranged to heat said lubricant with waste products of combustion from said fuel burner, control means for rendering said fuel burner operative in response to a refrigeration demand, and means responsive to a change in the condition of a part of said apparatus induced as a consequence of operation of said fuel burner for diverting waste products of combustion away from said lubricant heating 20 means and for rendering said driving device operative.

13. Absorption refrigerating apparatus comprising a boiler, a liquefier, an evaporator and a condenser connected in circuit, a fluid circulator sealed in said apparatus, a magnetically driven device for driving said fluid circulator sealed in said apparatus, a magnetic field producing means positioned exteriorly of the fluid retaining walls of said apparatus for applying a magnetic driving force to said magnetically driven device, a lubricant for said magnetically driven device, means for heating said generator, means for rendering said heating means operative in response to a demand for refrigeration, and means responsive to a change in the condition of a part of said apparatus induced as a consequence of operation of said heating means for rendering said lubricant heating means inoperative and for energizing said magnetic field producing means.
